UNITED STATES PATENT OFFICE.

ELIJAH C. HALL, OF BRAINTREE, MASSACHUSETTS.

HINGE.

No. 810,052.

Specification of Letters Patent.

Patented Jan. 16, 1906.

Application filed November 12, 1904. Serial No. 232,469.

To all whom it may concern.

Be it known that I, ELIJAH C. HALL, a citizen of the United States, residing in Braintree, in the county of Norfolk and State of Massachusetts, have invented an Improvement in Hinges, of which the following description, in connection with the accompanying drawings, is a specification, like characters on the drawings representing like parts.

10 This invention relates to blind-hinges, and has for its object to provide a hinge of a construction, as will be described, whereby the blind is securely locked in its closed or open position by the hinge until positively unlocked by longitudinal movement of the blind. For this purpose the hinge is provided with one member which is attached to the house or window-casing and is provided with a pintle having a non-circular section 15 which is adapted to fit in a correspondingly-shaped section of the other member of the hinge and prevent rotary movement of said second member until said second member, which is attached to the blind, is moved longitudinally to bring an enlarged section of its socket into coöperation with said non-circular section of the pintle to permit the blind to be revolved, as will be described more fully hereinafter. Provision is also made for preventing the blind from being accidentally unhinged, as will be described.

These and other features of this invention will be pointed out in the claims at the end of this specification.

35 Figure 1 is a front elevation of a blind provided with hinges embodying this invention, the blind being shown in its closed position; Fig. 2, a side elevation of the blind shown in Fig. 1 looking toward the right; Fig. 3, a detail to be referred to; Fig. 4, a front elevation of the blind in its open and raised position, and Figs. 5, 6, and 7 sectional details to be referred to.

40 Referring to the drawings, *a* represents a blind which is hung to the casing *b* by hinges embodying this invention.

In accordance with this invention each hinge is composed of one member *c*, which is attached to the house or casing *b*, and a coöperating member *d*, which is secured to the blind.

45 Referring to Figs. 2, 5, 6, and 7, the member *c* is provided with a screw or spur 12, adapted to be forced into the house or casing *b*, and a pintle 13, which is adapted to enter the socketed member *d*, attached to the blind.

The pintle 13 is provided intermediate its ends with a non-circular and preferably rectangular section 16 and above and below the same with circular sections 17 18, the bottom or lower portion 19 of the pintle being also non-circular in cross-section. The non-circular sections 16 19 of the pintle are designed to fit correspondingly-shaped sections 20 21 in the socketed member *d*, and above and below the non-circular section 20 of the socketed member the said member is provided with enlarged circular portions 22 23 of a diameter sufficient to permit the socketed member to rotate freely about the pintle.

70 In the normal or lowered position of the socketed member of the hinge the non-circular portions 20 21 coöperate with the non-circular portions 16 19 of the pintle, as shown in Fig. 5, and when in this position the socketed member is incapable of being rotated, and the blind is thereby locked from turning. If it is desired to turn the blind from its closed to its open position, or vice versa, the socketed member of the hinge is moved longitudinally of the pintle until the non-circular portions 20 21 are engaged with or brought into the same horizontal plane as the circular portions 17 18 of the pintle, which position is represented in Figs. 4 and 6, 80 and when in this position the socketed member of the hinge and the blind may be rotated or turned about the pintle, so as to open or close the blind, as the case may be.

85 Provision is made to limit the longitudinal movement of the socketed member on the pintle, and for this purpose the pintle is provided with a lip or projection 30, which co-operates with a shoulder 31, constituting the bottom wall of the enlarged section 22 and 90 extended around the said section on three sides, leaving the fourth side plain and extended to the mouth of the socketed member, as represented in Fig. 7, so that when the plain side wall of the socket in the socketed member is brought into line with the lip or projection 30 the socketed member can be removed from the pintle and the blind unhung.

95 The blind is hung by bringing the plain wall of the socket in the socketed member into line with the lip or projection 30 and dropping the blind down until the non-circular portion 22 of the socket engages or is brought into the same horizontal plane as the circular portion 17 of the pintle, whereupon the blind may be turned into its opened or 100 105 110

closed position, after which the blind may be lowered still further and into the position shown in Fig. 5, wherein it will be seen that the non-circular portions 20 21 of the socketed member engage the non-circular portions 16 19 of the pintle and securely lock the socketed member from turning, thereby firmly holding the blind in either its closed or open position and preventing or reducing to a minimum rattling of the blind.

Provision is made for elevating the blind, and for this purpose I have shown one form of device, (see Figs. 1 and 3,) which consists of a lever, preferably made of a wire rod, which is provided with one or more coils 40, through which is passed a staple 41, the coil constituting a pivot for the lifting-lever, one arm 42 of which is provided with a finger-piece 43 and the other arm of which is provided with a substantially horizontal coil 44 to engage the under side of the blind in its closed position, (see Fig. 1,) the said arm being extended beyond the coil 44 and provided with a finger 46 to engage the under side of the blind in its open position. (See Fig. 4.)

By reference to Fig. 3 it will be seen that the finger 43 extends laterally beyond the blind in both directions, so that the lifting-lever may be operated from the inside or outside of the house with the blind closed.

In Fig. 4 the blind is shown in its open position and as raised, the lifting-lever being in its depressed position.

I have herein shown one form of lifting device; but I do not desire to limit my invention in this respect. I may prefer to employ two non-circular sections 16 19 on the pintle; but, if desired, the section 19 may be made circular in form.

I claim—

1. In a hinge, in combination, a member

provided with a pintle having a non-circular section and a circular section, and a coöperating socketed member provided with a non-circular section to coöperate with the non-circular section of the pintle and lock the socketed member from turning, and having an enlarged section to coöperate with the non-circular section of said pintle to permit the socketed member to turn, substantially as described.

2. In a hinge, in combination, a member provided with a pintle having a non-circular section and a circular section, a coöperating socketed member provided with a non-circular section to coöperate with the non-circular section of the pintle and lock the socketed member from turning, and having an enlarged section to coöperate with the non-circular section of said pintle to permit the socketed member to turn, a lip or projection on the circular section, and a shoulder in the socketed member, substantially as described.

3. In a hinge, in combination, a stationary member provided with a pintle having a non-circular section intermediate its ends, and a movable socketed member closed at its upper end and provided with a non-circular section coöperating with the non-circular section of the pintle to lock the socketed member from turning and having an enlarged section to coöperate with the non-circular section of said pintle to permit the socketed member to turn, substantially as described.

In testimony whereof I have signed my name to this specification in the presence of two subscribing witnesses.

ELIJAH C. HALL.
